TELEPHONE HANDSET SUPPORTING DEVICE

Herman H. Renneker, Palm Springs, Calif., assignor to
H. H. Renneker Co., Inc., San Diego, Calif., a corporation of California

Filed June 20, 1958, Ser. No. 51,450

Term of patent 14 years

(Cl. D26—14)

The face opposite that shown in Figures 3 and 4 is the same as that shown in Figures 3 and 4 except as to right and left hand reversal.

The dot-dash line showing of a telephone handset in Figure 2 is for the purpose of illustration only.

The dominant features of my design reside in those portions shown in full lines.

I claim:

The ornamental design for a telephone handset supporting device, as shown and described.
